W. H. BECHTEL, OF PHILADELPHIA, PENNSYLVANIA.

Letters Patent No. 79,436, dated June 30, 1868.

IMPROVEMENT IN STEAM SAFETY-VALVES.

The Schedule referred to in these Letters Patent and making part of the same.

TO ALL WHOM IT MAY CONCERN:

Be it known that I, W. H. BECHTEL, of Philadelphia, Pennsylvania, have invented an Improved Safety-Valve; and I do hereby declare the following to be a full, clear, and exact description of the same.

My invention consists of a safety-valve, constructed in the peculiar manner fully described hereafter, with the view of dispensing with the usual weighted lever, and employing a weight bearing directly on the valve, the said weight and valve being so well guided that they can be used on locomotive and marine boilers without fear of disarrangement and injury by being agitated and jarred. A further object of my invention is to prevent unauthorized parties from tampering with the valve.

In order to enable others skilled in the art to make and use my invention, I will now proceed to describe its construction and operation, reference being had to the accompanying drawing, which forms a part of this specification, and in which—

Figure 1 is a vertical section of my improved safety-valve.

Figure 2, a vertical section of the valve-chest.

Figure 3, a plan view; and

Figure 4 a sectional plan on the line 1-2, fig. 1.

Similar letters refer to similar parts throughout the several views.

The base, A, of the valve-chest is secured to the boiler, and to the top of this base is attached a casing, B, having at the top an opening, b.

Within the base, A, is a chamber, a, communicating with the steam-space of the boiler, and in this chamber, and forming part of the base, is a hollow cross-piece, d, in which is an opening, and on the edge of the latter is a bevelled seat for the valve e, formed at the lower end of the tube D. In the top of the base, A, is an opening, on the edge of which is formed the seat, f, for a valve, h, also formed on the tube D, beneath a collar, i, on the latter, which collar supports the annular weight E, ribs m on the tube projecting into grooves in the weight, as seen in fig. 4.

These ribs, m are carried upwards above the tube, and, projecting into the opening b in the casing B, serve to guide and steady the valve, the lower portion of which is guided by its ribs n, adapted to the opening in the top of the base, A, and by projections q, adapted to the opening in the hollow cross-piece d. A horizontal spindle, G, fig. 3, is arranged to turn in the edge of the mouth b of the casing A, and on this spindle is an arm, H, connected by a rod, i, to a central piece, p, which is connected by webs to and forms a part of the tubular duplex valve. The spindle G is also furnished with an arm, K, to which may be attached a cord, extending to any convenient point, and enabling the attendant engineer to raise the tube D at pleasure.

It will be observed that the valve h is of larger diameter than the valve e, and hence that the area exposed to the pressure of steam is equal to the difference between the areas of the two valves, the weight E being determined by the pressure of steam which the boiler has to carry, and the extent of the difference between the areas of the said valves.

When the valve is elevated by an excessive pressure of steam, the latter at once escapes, one volume into the hollow cross-piece d, and thence through the tube D and mouth b of the casing, and the other volume through the opening in the top of the base, A, and thence through the annular space between the weight E and casing B, to the same mouth b.

It will thus be seen that a slight elevation of the tube D will insure the ready escape of the steam through uninterrupted channels.

The valves may be so proportioned, as regards their respective areas, that a weight comparatively small in bulk may be used, and this weight has a direct bearing on the valve, instead of acting on the same through the medium of a lever, the objections to which are too well known to engineers to require explanation.

The tube D is so well guided, both above and below, that my improved valve can be used on locomotive-engines and marine boilers without any fear of disarrangement or deterioration of parts through jars or shocks.

A pipe may be continued upwards from the mouth *b* of the casing to a height which will prevent access to the valve, and frustrate all attempts to tamper with the same.

I claim as my invention, and desire to secure by Letters Patent—

1. The weighted tube *D*, with its two valves, *e* and *h*, in combination with the base, *A*, its chamber *a*, hollow cross-piece *d*, the within-described valve-seats *f*, and the casing *B*, the whole being constructed and arranged as and for the purpose herein set forth.

2. The webs or ribs on the tube *D*, adapted to the opening *b* of the casing *B*, as and for the purpose herein set forth.

3. In combination with the tubular valve *D*, the spindle *G*, rod *I*, and the arms *H* and *K*, for the purpose specified.

In testimony whereof, I have signed my name to this specification in the presence of two subscribing witnesses.

W. H. BECHTEL.

Witnesses.

W.M. A. STEEL,
